UNITED STATES PATENT OFFICE.

ARNOLD H. HOLMES, OF HIGHLAND PARK, AND WILSON D. CRAIG WRIGHT, OF PHILADELPHIA, PENNSYLVANIA; SAID WRIGHT ASSIGNOR TO HENRY HENDERSON, OF SCOTCH PLAINS, NEW JERSEY.

WINDOW-OPERATING DEVICE.

1,117,575.

Specification of Letters Patent.

Patented Nov. 17, 1914.

Application filed May 25, 1914. Serial No. 840,739.

To all whom it may concern:

Be it known that we, ARNOLD H. HOLMES, a citizen of the United States, residing at Highland Park, in the county of Delaware and State of Pennsylvania, and WILSON D. CRAIG WRIGHT, a citizen of the United States, residing at Philadelphia, in the county of Philadelphia and State of Pennsylvania, have invented certain new and useful Improvements in Window-Operating Devices; and we do hereby declare the following to be a full, clear, and exact description of the invention, such as will enable others skilled in the art to which it applies to make and use the same, reference being had to the accompanying drawings, and to characters of reference marked thereon, which form a part of this specification.

The present invention has reference, generally, to improvements in window operating devices; and, the invention relates more particularly to a novel and simple construction of mechanism adapted to be connected with a window whereby the same may be easily and quickly raised or lowered by a simple operation requiring little effort or muscular exertion.

The invention has for its principal object to provide a self-balancing opening and closing mechanism for connection with any type of window, but more particularly adapted for use with the windows and doors of limousine automobile bodies, coaches, railway carriages and similar vehicles. To this end the present invention provides a sprocket and chain mechanism for producing the throw or movement of the window, the same being operated by means of a handle means through a reduction gearing transmission whereby the weight of the window is offset by the power multiplication of said gearing. In addition to the above arrangement the said handle means is constructed so as to be self-locking for the purpose of maintaining the window locked in any position, open, closed or intermediate of said open and closed position.

Other objects of the present invention, not at this time more particularly enumerated, will be clearly understood from the following detailed description of the said invention.

The said invention consists, primarily, in the novel window opening and closing

mechanism hereinafter set forth; and, furthermore, the invention consists in the several novel arrangements and combinations of the various parts of the same, as well as in the details of the construction thereof, all of which will be fully described in the following specification, and then finally embodied in the claims which are appended to and which form an essential part of said specification.

The invention is clearly illustrated in the accompanying drawings, in which:—

Figure 1 is an elevation of said window opening and closing mechanism, a portion of the inclosing frame-work of the body or door in which it is mounted being removed to disclose the same, and the mechanism being illustrated as operated to close the window-member. Fig. 2 is a similar view, the mechanism being illustrated as operated to open the window-member. Fig. 3 is a view similar to that shown in Fig. 1, the window and frame being broken away, and the view being drawn on a greatly increased scale to more clearly illustrate the details of the mechanism. Fig. 4 is a horizontal section taken on line 4—4 in said Fig. 3, looking downward; Fig. 5 is a horizontal section taken on line 5—5 in said Fig. 3, looking downward; and Fig. 6 is a detail horizontal section similar to that shown in Fig. 5, but illustrating the handle means released from locked position, and in the course of rotation for the purpose of operating the window raising and lowering mechanism. Fig. 7 is a face view of the handle means; and Fig. 8 is a cross-section of the same, taken on line 8—8 in said Fig. 5, looking downward.

Similar characters of reference are employed in all of the hereinabove described views to indicate corresponding parts.

Referring now to the said drawings the reference character 1 indicates the body of a window or door frame provided with the opposite vertical grooves or channels 2 in which is slidably disposed the glass window-member 3, so that the latter is vertically movable therein.

The reference character 4 indicates the inner wall of the body of a window or door frame 1. Secured within the interior space of the window or door frame 1 between its outer and inner wall, and

mounted preferably upon said inner wall 4 is a base-plate 5, the same being secured in said mounted position by means of screws 6, or any other desirable form of fastening means. Connected with said base-plate 5, so as to project therefrom at a suitable location, is a stud or journal 7, and mounted to rotate upon said journal or stud 7 is a sprocket-wheel 8, of suitable diameter so as to provide a circumference which equals or slightly exceeds the maximum distance of the throw or movement of said window-member 3 in its guides 2.

The reference character 9 indicates a sprocket-chain adapted to run upon and be operated by said sprocket-wheel 8. Said sprocket-chain 9 is secured by one end, by means of anchor-links 10, to the body of said sprocket-wheel 8, and the sprocket-chain 9 then extends, normally, around the circumference of said sprocket-wheel 8 and in proper engagement with the sprocket-teeth 11 of the latter. Connected with the free end of said sprocket-chain 9 is a transversely extending cross-pin 12, which projects outwardly from the outer side of said chain and sprocket means. Rotatably mounted upon the free end of said cross-pin 12 is an anti-friction roller 13, having guide flanges 14, the same being arranged in engagement with a horizontally extending slot 15 of a pull-piece 16, which is secured, in any suitable manner, to the channeled carrier-bar 17, in which the lower end 35 of the glass window-member 3 is secured. Said slot 15 of said pull-piece 16 is provided at one end with an enlarged hatch-portion 18 through which said flanged anti-friction roller 13 may be inserted to carry 40 the same into said slot 15, so that its flanges 14 engage the marginal edges of said slot to thus prevent displacement of said anti-friction roller 13 from its properly associated relation to said pull-piece 16.

45 Mounted upon said base-plate 5, and spaced therefrom by the spacing-block 19 and the holding angle-pieces 20, so as to lie in the plane of said sprocket-wheel 8 and tangent thereto, is a vertically extending chain-guide or runway 21, the wall 22 of which is cutaway at its upper end so that said sprocket-wheel 8 carrying the sprocket-chain 9 may enter therein. Also secured in the upper end of said chain-guide or runway 50 21 is a guide-block 23, which projects over said sprocket-wheel 8 and sprocket-chain 9, and the curved under surface 24 of which provides a guide for guiding the free end of said sprocket-chain 9 down into said 55 chain-guide or runway 21 so as to cause the former to enter the latter. Said chain-guide or runway 21 is provided in its front wall, 25 with a longitudinally extending slot or opening 26 through which passes or projects said cross-pin 12 connected with the

free end of said sprocket-chain 9, when the latter enters and travels in said chain-guide or runway 21.

The reference character 27 indicates a plate-member which is secured, by means of a fastening screw 28 to the outer end of said stud or journal 7, and being further secured at one end to a lug or block 29 projecting from said base-plate 5, by the screw 30, or other suitable fastening means. As thus positioned said plate-member 27 extends across the face of said sprocket-wheel 8, the latter being thereby retained against removal from said stud or journal 7, and the end of said plate-member 27 adjacent to said chain-guide or runway 21, is arranged to join with the front wall 25 of said chain-guide or runway 21 so as to form a guide-member 31, the curved guiding edge 32 of which lies tangent to said slot or opening 26, so as to be engaged by said cross-pin 12, thereby serving to guide the same into said slot or opening 26, and said sprocket-chain 9 into said chain-guide or runway 21 as said sprocket-chain is paid off from the rotated sprocket-wheel 8.

The reference character 33 indicates a gear-wheel which is also journaled upon said journal or stud 7 so as to rotate thereon. Said gear-wheel 33 is secured to said sprocket-wheel 8, so that a rotation of the former turns the latter, the fastening means comprising screws 34 in combination with spacing-members 35, whereby said sprocket-wheel and gear-wheel are not only secured together, but are also spaced away from each other so as to allow the unobstructed arrangement of said sprocket-chain 9 with said sprocket-wheel.

The reference character 36 indicates a pinion which meshes with said gear-wheel 33. Said pinion is provided with hub-portions 37 and 38, the hub-portion 37 being journaled in a bearing opening 39 provided therefor in said base-plate 5, and the hub-portion 38 being journaled in a bearing opening 40 formed in a yoke-block 41 which is secured to said base-plate 5 so as to straddle said pinion 36. Said pinion is provided with a rectangular opening 42 for the reception of the rectangularly formed end 43 of the stem 44 of a handle-member 45, the rotation of which serves to rotate said pinion 36, thereby in turn rotating said gear-wheel 33 and said sprocket-wheel 8 connected with the latter.

The reference character 46 indicates a plate-member having a centrally positioned tubular bearing-portion 47 in which said stem 44 of the handle-member 45 is journaled, said plate-member 46 being counter sunk in the outer surface of said inner wall 4 of the window or door frame 1.

The reference character 48 indicates a face-plate adapted to be registered over said

plate-member 46, said face-plate having an outwardly projecting centrally disposed chambered portion or casing 49 formed in connection therewith, and through which said stem 44 of said handle-member 45 extends. The end wall of said casing portion 49 is provided with a plurality or series of stop-receiving-perforations 50. Secured to said stem 44 of said handle-member 45, so as to be located within said casing portion 49 is a disk or flange 51 arranged to rotate with said stem and handle-member. Said disk or flange 51 carries thereon an outwardly projecting stop-stud 52 which may be selectively registered with any one of said stop-receiving perforations 50, so as to enter the same, and thereby lock said stem and handle-member at the end of various degrees of operation or rotation of the same. A coil-spring 53 arranged in back of said disk or flange 51, causes an outward longitudinal movement of said stem and handle-member when the latter is released, whereby said stop-stud 52 is projected into one of the said stop-receiving openings. Said stem and handle-member being therefore capable of a longitudinal movement, as well as a rotating movement, such movement is allowed for when connecting said rectangularly formed end 43 of said stem in said rectangular opening 42 of said pinion 36, so that the requisite amount of longitudinal play of the former in the latter is provided for, while yet maintaining their coupled relation so that the rotation of said handle-member and stem will rotate said pinion, 36, and consequently said gear-wheel 33 and sprocket-wheel 8 driven thereby.

In the operation of the above described mechanism, assuming that the window is closed, as shown in Fig. 1, and it is desired to open the same, as shown in Fig. 2, said handle-member 45 is first pushed inward to produce a longitudinal movement of said stem 44 which carries inward said disk or flange 51 against the compression of the coil-spring 53, thereby withdrawing said stop-stud 52 from engagement with one of said stop-receiving-perforations 50, and consequently freeing said handle-member 45 from its locked condition, allowing the same to be rotated. The rotation of said handle-member 45 and its stem 44 rotates said pinion 36, which meshing with said gear-wheel 33 transmits the rotary movement thereto and consequently turns said sprocket-wheel 8. In thus turning said sprocket-wheel 8 the sprocket-chain 9 is paid off of the same, and the free end of said sprocket-chain moves toward the guide-block 23, the curved surface 24 of which holds said chain in engagement with the teeth of said sprocket-wheel 8 until the entrance of said chain-guide or runway 21 is reached. Since the free end 66 of said sprocket-chain 9 carries said cross-

pin 12 and anti-friction roller 13 which is coupled with the pull-piece 16 of the window-member 3, the downward movement of the free end of said sprocket-chain, as it follows around the moving sprocket-wheel 8, exerts a downward pull upon said window-member 3 which starts its lowering or opening movement. The forward movement of said free end of said sprocket-chain, cross-pin and anti-friction roller, being compensated for by the traveling movement of said roller 13 in the slot 15 of said pull-piece, since the movement of said free end of the chain becomes vertical only after entering said chain-guide or runway 21. As the rotation of said sprocket-wheel 8 continues said free end of the sprocket-chain 9 is carried downward into said chain-guide or runway 21, and said cross-pin 12 engages said guiding edge 32 of the guide-member 31 so as to cause the same to ride into said slot or opening 26 of the front wall 25 of said chain-guide or runway 21, with the effect of causing the sprocket-chain 9 to leave or remove from said sprocket-wheel 8 and continue to travel downwardly in said chain-guide or runway 21. Said sprocket-chain 9 being inclosed by said chain-guide or runway 21, the same is prevented from buckling or bending, so that the body of the same is forced to travel downwardly in said chain-guide or runway 21, the free end carrying said cross pin 12 and roller 13 also traveling downward and therefore continuing to pull downward upon said pull-piece 16 and the window-member 3 connected therewith, whereby the latter is moved to its open position.

Since the pinion 36 is reduced in proportion to the gear-wheel 33, the power applied by the handle-member is multiplied so that a very little exertion will accomplish the movement of the window either up or down, and, furthermore, the positive connection of the chain with the sprocket-wheel 8, and the geared connection of the latter with the handle-member in effect balances the window-member so that the same is maintained in the position to which it is moved, but even if such were not the case, the self-locking feature of the handle-member when the spring 53 forces the stop-stud into a stop-receiving opening, as above described, will serve to positively hold the mechanism against rotation in either direction, and consequently will prevent the window-member 3 from moving away from any position to which it has been opened or closed.

To close the window-member, the opening operations above described are reversed, that is the handle-member and pinion are rotated in the opposite direction, to turn in the opposite direction the gear-wheel 33 and sprocket-wheel 8 whereby the sprocket-chain is wound up on said sprocket-wheel, and by the direct pull of such operation the

window-member is also moved upward to closed position or any intermediate closed position.

It will be apparent that the above apparatus is simple both in construction and operation, requiring little effort to operate and being positive in the application of the multiplied moving force to the window. The apparatus is compactly arranged, and little liable to disarrangement whereby it would be rendered inoperative; no matter under what conditions it is used, whether in connection with a moving, vibrating vehicle, or in a stationary window frame and window.

We are aware that some changes may be made in the various arrangements and combinations of the several devices and parts of our present invention without departing from the scope of the same as described in the foregoing specification, and as defined in the claims appended hereto. Hence, we do not limit our invention to the exact arrangements and combinations of the various devices and parts as herein described, and as illustrated in the accompanying drawings, nor do we confine ourselves to the exact details of the construction of the said parts.

30. We claim:

1. A device for opening and closing windows comprising a sprocket-wheel, a sprocket-chain mounted on said sprocket-wheel, one end of said chain being secured to said sprocket-wheel, means for connecting the free end of said chain with the window to be operated, means for rotating said sprocket-wheel, and means for guiding said chain when paid off of said sprocket-wheel.
2. A device for opening and closing windows comprising a sprocket-wheel, a sprocket-chain mounted on said sprocket-wheel, one end of said chain being secured to said sprocket-wheel, a vertically disposed chain-guide or runway mounted tangent to said sprocket-wheel, guiding devices for turning said chain into said chain-guide or runway when paid off of said sprocket-wheel, means for connecting the free end of said chain with the window to be operated, and means for rotating said sprocket-wheel.
3. A device for opening and closing windows comprising a base-plate adapted to be mounted on the wall of the window-frame, a journal projecting from said base-plate, a sprocket-wheel rotatably mounted on said journal, a sprocket-chain mounted on said sprocket-wheel, one end of said chain being secured to said sprocket-wheel, the free end of said chain carrying a cross-pin having means for engaging the window to be operated, a vertically disposed chain-guide or runway secured to said base-plate tangent to said sprocket-wheel and provided at its up- per end with an opening into which said sprocket-wheel and chain projects, a guide-block at the upper end of said chain-guide or runway, the front wall of said chain-guide or runway having a longitudinally extending slot, a guide-member having a curved guiding edge tangent with the entrance to said slot, said guiding edge being adapted to turn said cross-pin into said slot when said free end of said chain enters said chain-guide or runway as said chain is paid off of said sprocket-wheel, and means for rotating said sprocket-wheel.
4. A device for opening and closing windows comprising a base-plate adapted to be mounted on the wall of the window-frame, a journal projecting from said base-plate, a sprocket-wheel rotatably mounted on said journal, a sprocket-chain mounted on said sprocket-wheel, one end of said chain being secured to said sprocket-wheel, the free end of said chain carrying a cross-pin having means for engaging the window to be operated, a vertically disposed chain-guide or runway secured to said base-plate tangent to said sprocket-wheel and provided at its upper end with an opening into which said sprocket-wheel and chain projects, a guide-block at the upper end of said chain-guide or runway, the front wall of said chain-guide or runway having a longitudinally extending slot, a guide-member having a curved guiding edge tangent with the entrance to said slot, said guiding edge being adapted to turn said cross-pin into said slot when said free end of said chain enters said chain-guide or runway as said chain is paid off of said sprocket-wheel, and means for rotating said sprocket-wheel.
5. A device for opening and closing windows comprising a sprocket-wheel, a sprocket-chain mounted on said sprocket-wheel, one end of said chain being secured to said sprocket-wheel, the free end of said chain carrying an outwardly projecting

- cross-pin, a pull-piece for attachment to a window, means carried by said cross-pin for coupling said pull-piece with the free end of said chain, a vertically disposed chain-guide or runway mounted tangent to said sprocket-wheel and provided in its upper end with an opening into which said sprocket-wheel and chain projects, a guide-block at the upper end of said chain-guide 5 or runway, the front wall of said chain-guide or runway having a longitudinal slot in which said cross-pin may ride, a guide-member having a curved guiding edge tangent to the entrance to said slot, said guiding-edge being adapted to turn said cross-pin into said slot, and means for rotating said sprocket-wheel.
6. A device for opening and closing windows comprising a sprocket-wheel, a sprocket-chain mounted on said sprocket-wheel, one end of said chain being secured to said sprocket-wheel, the free end of said chain carrying an outwardly projecting cross-pin, a pull-piece for attachment to a window, means carried by said cross-pin for coupling said pull-piece with the free end of said chain, a vertically disposed chain-guide or runway mounted tangent to said sprocket-wheel and provided in its upper end with an opening into which said sprocket-wheel and chain projects, a guide-block at the upper end of said chain-guide or runway, the front wall of said chain-guide or runway having a longitudinal slot in which said cross-pin may ride, a guide-member having a curved guiding edge tangent to the entrance to said slot, said guiding-edge being adapted to turn said cross-
- pin into said slot, and means for rotating said sprocket-wheel, comprising a gear-wheel connected with said sprocket-wheel so as to rotate therewith, a pinion for driving said gear-wheel, and a handle-member having a stem coupled with said pinion, and means for locking said handle-member 40 against rotation.
7. A device for opening and closing windows comprising a sprocket-wheel, a sprocket-chain mounted on said sprocket-wheel, one end of said chain being secured to said sprocket-wheel, means for connecting the free end of said chain with the window to be operated, means for guiding said chain when paid off of said sprocket-wheel, transmission gearing for rotating said 50 sprocket-wheel, and a handle-member for operating said transmission gearing.
8. A device for opening and closing windows comprising a sprocket-wheel, a sprocket-chain mounted on said sprocket-wheel, one end of said chain being secured to said sprocket-wheel, means for connecting the free end of said chain with the window to be operated, means for guiding said chain when paid off of said sprocket-wheel, 60 a handle-member for operating said transmission gearing, and means for locking said handle-member against rotation.

In testimony, that we claim the invention set forth above we have hereunto set our 70 hands this seventh day of May, 1914.

ARNOLD H. HOLMES.

WILSON D. CRAIG WRIGHT.
